Edward Durell, Columbus, Ohio, assignor to The
Union Fork & Hoe Company, Columbus, Ohio,
a corporation of Ohio

Application May 13, 1938, Serial No. 77,156

Term of patent 7 years

To all whom it may concern:

Be it known that I, Edward Durell, a citizen of the United States, residing at Columbus, in the county of Franklin and State of Ohio, have invented a new, original, and ornamental Design for a Display Rack for Farm and Garden Tools, of which the following is a specification, reference being had to the accompanying drawing, forming a part thereof.

Fig. 1 is a perspective view of the display rack

for farm and garden tools showing my new design;

Fig. 2 is an end elevation thereof;
Fig. 3 is a top plan view.

I claim:

The ornamental design for a display rack for farm and garden tools, as shown.

EDWARD DURELL.
